PERCUSSION TOOL

David L. Garrett, Denver, Colo.

Application January 24, 1942, Serial No. 428,026

9 Claims. (Cl. 172—36)

This invention relates to apparatus of hammer type adapted to deliver a rapid succession of blows to and for work effect on a tool associated with the apparatus, and has as an object to provide an improved construction and arrangement of elements constituting such an apparatus.

A further object of the invention is to provide improved means for actuating a reciprocable impact element for work effect on a tool.

A further object of the invention is to provide an improved arrangement of means operable to transform continuous rotary motion into reciprocatory motion of an impact or hammer element.

A further object of the invention is to provide an improved construction and arrangement of elements for associating an electric motor in driving relation with a reciprocable impact element.

A further object of the invention is to provide an improved power hammer adapted for operative association with a variety of specific tool elements.

A further object of the invention is to provide an improved power hammer that is small in size in proportion to its power output, compact in form, relatively light in weight, simple of construction and operation, substantially free from adverse vibratory characteristics, positive and efficient in use, and available for operation wherever electric power is obtainable.

My invention consists in the construction, arrangement, and combination of elements herein-after set forth, pointed out in my claims, and illustrated by the accompanying drawings, in which:

Figure 1 is a section taken axially and longitudinally through one embodiment of the invention. Figure 2 is a fragmentary, detail section, on an enlarged scale, taken substantially on the indicated line 2—2 of Figure 1. Figure 3 is a cross section, on the same scale as Figure 2, taken substantially on the indicated line 3—3 of Figure 1. Figure 4 is a longitudinal section taken axially through an alternative embodiment of the invention. Figure 5 is a cross section, on an enlarged scale, taken substantially on the indicated line 5—5 of Figure 4. Figure 6 is a longitudinal section taken axially through a modified form of the typical hammer shown in Figure 4. Figure 7 is a fragmentary, detail section, on an enlarged scale, taken on the indicated line 7—7 of Figure 6.

In the construction of the improved apparatus as shown in Figures 1—3, inclusive, the numeral 10 designates a rigid, tubular shell or casing

formed of any suitable material, such as metal, cylindrical in form, open at each end, and provided with a straight, uniform, cylindrical bore. The shell 10 is normally closed at one end by 5 means of a cap plate 11 mounted for removal and replacement to permit access to the corresponding end of the shell, and is closed at its other end by a relatively heavy plug 12 which threadedly, or otherwise, removably and replaceably 10 engages with the shell. A web 13 is disposed transversely of and within the shell 10 between the cap 11 and the plug 12, thereby dividing the shell interior into two compartments, and the web 13 is disposed more nearly adjacent the cap 11 than the plug 12 to provide a larger of 15 said compartments adjacent said plug. The web 13 is centrally apertured and recessed to receive and seat an anti-friction bearing assembly 14 and the inner face of the plug 12 is formed with 20 a central recess wherein is seated an anti-friction bearing assembly 15, said assemblies 14 and 15 being thus disposed to engage and rotatably support opposite end portions of a hollow shaft 16 which is thereby mounted to extend longitudinally, 25 and axially through the larger compartment of the shell 10. The shaft 16 functions as the driven shaft of an electric motor and directly carries elements 17 constituting the armature and elements 18 constituting the commutator of 30 a typical motor assembly whereof the field elements 19 are fixedly associated with the shell 10 in operative relation with the armature elements 17. The motor elements of the apparatus are illustrated conventionally and may be of any 35 specific type and construction suitable to their purpose, which is to effect rotation of the shaft 16 when electrical energy is supplied thereto. The motor should preferably be characterized by high starting torque, small diameter, and relatively slow speed, such motors being available and well known. One end of the shaft 16 extends through the web 13 and into the shell compartment between said web and the cap 11, and 40 said end of said shaft is formed as or rigidly secured to a cylindrical cup 20 substantially filling the diameter of the shell and opening toward the cap 11. The plug 12 is centrally apertured to provide 45 an opening registering with the bore of the shaft 16, and said plug is formed with an axial, cylindrical, exterior extension 21 which is provided with an end-opening, axial bore somewhat greater in diameter than the aperture registering with the shaft bore, and a bearing sleeve 22 is seated within, extends throughout the length of 50 55

and is preferably associated for convenient removal and replacement with the bore of the plug extension 21. The bore of the sleeve 22 is straight and uniform in diameter, and is adapted to receive and slidably accommodate a reciprocable impact head 23 carried by and in fixed relation with one end of a stem 24 which extends through the shaft 16 and cup 20 to terminate adjacent the cap 11, said stem 24 preferably being supported near its end remote from the head 23 by a bushing or equivalent device carried centrally of the cup 20 and in bearing engagement against said stem. The sleeve 22 is formed with longitudinally-disposed slots 25 opening through portions of the sleeve wall intermediate the sleeve ends, and lugs 26 fixed to and extending radially from the head 23 slidably engage within the slots 25 and hold said head 23 against rotation within the sleeve while accommodating reciprocation of said head axially of the sleeve. The head 23 is of a diameter greater than that of the stem 24 and substantially fills the bore of the sleeve 22, thereby providing an annular space within said sleeve and about said stem between the head 23 and the web of the plug 12, in which space is mounted an expansive coil spring 27 disposed to bear against the web of the plug 12 and the shoulder of the head 23 to normally urge said head and its stem 24 outwardly along the sleeve 22. A cross-head 28 is fixed to and in perpendicular relation with the end of the stem 24 adjacent the cap 11 and extends diametrically of the cup 20, outer ends of said cross-head 28 being provided with rollers 29 disposed to engage and bear against the adjacent circular margin of the cup 20. It is the function of the cup 20, when rotating, to retract the head 23 and stem 24 against the pressure of the spring 27, and for this purpose the circular margin of said cup is contoured to provide a suitable cam track 30 wherewith the rollers 29 engage. The cam track 30 is shown in the drawings as having two diametrically opposed peaks and complementary valleys in immediate trailing relation therewith, so that each rotation of the cup 20 is productive of two reciprocatory cycles of the impact assembly.

As will be apparent, impact effect deriving from reciprocation of the head 23 and stem 24 may be applied in various ways to the end of a tool shank suitably received within the open end of the sleeve 22, an arrangement suitable for such purpose being illustrated in association with a riveting head in Figure 1. As illustrated, a tappet block 31 is slidably received in the open-end portion of the bore of the sleeve 22 and therein positioned to receive the blows delivered by the head 23. The outer end of the block 31 is formed with a threaded socket, or equivalent arrangement, whereby a tool member 32 may be removably and replaceably secured to the block. Studs 33 project radially from the block 31 and engage through the slots 25 of the sleeve 22, said studs projecting beyond the outer surface of said sleeve for engagement of their outer ends within a ring 36 thereby positioned to slide with the block 31 on and exteriorly of the sleeve 22. An adjusting thimble 37 threadedly engages on and exteriorly of the free end of the sleeve 22 in spaced relation with the ring 36, and an expansive coil spring 38 surrounds the sleeve 22 in bearing engagement between the ring 36 and thimble 37 to normally urge said ring away from said thimble. A housing sleeve 39 telescopes over and is secured at one end to the thimble 37, said sleeve

extending across the spring 38 and ring 36 to telescoping engagement of its other end with and about the end of the plug extension 21, and said sleeve 39 detachably engages and serves to position a ring 40 disposed between the ring 36 and the end of the plug extension 21, so that an expansive coil spring 41 exteriorly surrounding the sleeve 22 between the rings 36 and 41 acts to balance the pressure of the spring 38 and yieldably position the tappet block 31 for limited reciprocation axially of the sleeve 22. The tappet block 31 and tool carried thereby is thus provided with a cushioned mounting, so that impact effects and consequent vibrations are not transmitted in their full magnitude to other elements of the apparatus, and the tappet mounting also provides for adjustment, through rotation of the threaded thimble 37, in the position of the block 31 within the sleeve 22 for variation of the maximum spacing between said block and the impact head 23, with consequent variation in the travel of said head prior to impact and corresponding control of the force of the blow delivered.

One or more handles 42 may be associated with the shell 10 and positioned as desired for convenience in holding and manipulating the apparatus and a switch trigger 43 may conveniently be associated with a handle 42 for control of current supply to the motor elements of the assembly.

The embodiment of the apparatus shown in Figures 4 and 5 is the same in operative principle as that hereabove described and differs principally in that the reciprocatory assembly is mounted for rotation with the motor shaft 16 while the cup carrying the cam track 30 is held stationary. In the alternative embodiment, the shell 10, cap 11, plug 12, web 13, bearing assemblies 14 and 15, hollow shaft 16, and motor elements 17, 18 and 19, are functionally and structurally substantially the same as shown in Figure 1 and above described. Instead of the cup 20 carried by and for rotation with the shaft 16, the web 13 is provided with a concentric, annular cup extension 20' directed toward the cap 11, the annular margin of said extension being formed to provide the desired cam track 30. The motor shaft 16 has an axial bore sufficient in size to receive and slidably accommodate an impact head 23' which is mounted to rotate with said shaft and reciprocate relative thereto by means of rollers, or equivalent devices 44 carried by the inner ends of studs 45 fixed in circumferentially spaced relation radially of said shaft, the head 23' being formed with longitudinal slots or splines wherein said rollers 44 engage. A stem 24', of less diameter than the head 23', fixedly engages the end of said head adjacent the web 13 and extends axially of the shaft 16 through a hole in the web 13 and through a bearing in the cap 11, so that said stem is supported and guided for rotation and reciprocation. A housing cap 46 removably and replaceably engages the cap 11 in covering relation with the otherwise exposed end of the stem 24' and the bearing supporting said stem. A cross-head 28 is fixed to and for rotation with the stem 24' between the cam track 30 and the cap 11, and said cross-head is provided with rollers 29 adjacent its outer ends and positioned for rolling engagement against the cam track 30 when the stem 24' is caused to rotate. The head 23' is normally urged toward the plug 12 and into engagement of the rollers 29 against the cam track 30 by means of an expansive coil spring 47 which surrounds the stem 24' within the shaft

16 and acts between the shoulder of the head 23' and the web 13, an anti-friction bearing assembly 48 preferably being interposed between the web 13 and the adjacent end of the spring 47 to facilitate rotation of said spring relative to said web. With the arrangement shown and described, activation of the motor results in rotation of the shaft 16, head 23', stem 24', and cross-head 28 carrying the rollers 29, so that said rollers 29 are caused to traverse the cam track 30 with consequent retraction of the head 23' against the pressure of the spring 47 until the peaks of the cam track have been passed, whereafter said spring acts to drive the head 23' axially within the shaft 16 and toward the plug 12.

In the construction according to Figure 4, the bows of the head 23' are received on the inner end of a cylindrical plug or tappet 49 which engages at its inner end through a bearing formed centrally of the plug 12 and extends within the bore of the shaft 16. The tappet 49 is loosely housed within a sleeve 50 which threadedly engages at its inner end with an interiorly-threaded boss 51 projecting axially from the plug 12, and the outer end of the tappet 49 is slidably received in and supported by a thimble 52 which threads into the outer end of the sleeve 50. An annular rib 53 is formed on and projects circumferentially from the tappet 49 within the sleeve 50 and between the end of the thimble 52 and the web of the plug 12, so that expansive coil springs 54 and 55, surrounding the tappet 49 on opposite sides of the rib 53, may function to yieldably position said tappet 49 while permitting travel of said tappet under the influence of impacts driving from the head 23'. The outer end portion of the thimble 52 is formed to receive and guide the end of a tool shank, such as a hexagonal bar 56, and a tool retainer of conventional type, indicated at 57, may be engaged with the outer end of the thimble 52 to prevent accidental separation of the tool 56 from said thimble.

The structural and operative relation of the elements constituting the apparatus illustrated in Figure 6 is closely similar to that shown in Figure 4, and differs from said latter figure chiefly in that the showing of Figure 6 includes means for rotating the tool acted upon by the apparatus, means for feeding fluid to and through the tool shank, and convenient means for adjusting the effective pressure of the spring acting to drive the impact head. To provide means for rotating the tool shank, the plug 12 is replaced by a web 12' which carries the bearing assembly 15 in supporting relation with one end of the hollow shaft 16 and which is centrally apertured to accommodate an end extension of said shaft 16 which carries a hollow gear 58. The shell 10 is extended for a distance beyond the web 12' to provide an end compartment which is closed by the removable cap 59 formed with a central aperture defined and lengthened by means of an exteriorly-projecting annular flange 60. A gear 61, larger in diameter than the gear 58, is formed on or fixed to the inner end of a sleeve 62 which engages through and is mounted for rotation in the flange 60 and central aperture in the cap 59, said gear 61 being thus disposed in parallel, adjacent relation with the gear 58. A plurality of 70 units, having each a larger pinion 63 and a smaller pinion 64 connected for simultaneous rotation in adjacent, parallel relation, are mounted for rotation on shafts 65 engaging between the web 12' and cap 59 in parallel relation with the axis 75

of the shaft 16, and said units are disposed with their larger gears 63 meshing with the gear 58 and their smaller gears 64 meshing with the gear 61, so that rotation of the shaft 16 operates 5 through the meshed gears to rotate the sleeve 62 in the same direction as and at a speed less than that of said shaft 16. The outer end of the sleeve 62 extends beyond the end margin of the flange 60 and detachably engages with a tool retainer 57 in such manner as to hold the gear 61 against a thrust ring bearing on the inner face of the cap 59, thereby holding the sleeve 62 and gear 61 against end play. The sleeve 62 and gear 61 are formed with an axial bore angular in cross 15 section and adapted to slidably receive the corresponding angular end of a tool shank 56, so that rotation of said sleeve and gear is transmitted to and for rotation of the tool shank engaged therethrough.

20 Means for the convenient manual adjustment of the pressure exerted by the spring 47 on the head 23' is shown as comprising a follower ring or abutment 66 slidably mounted on the stem 24' within the end of the shaft 16 adjacent the 25 web 13 in position to bear against the corresponding end of the spring 47, a plurality of thrust rods 67 in parallel relation with and exteriorly of the stem 24' and rigidly connecting the abutments 66 with a slide ring 68 movable on the stem 24' 30 within a cylindrical bore formed centrally of the cap 11, and an anti-friction thrust bearing assembly 69 operatively engaging the face of the slide ring 68 remote from the abutment 66. The rods 67 preferably pass slidably through the 35 hub of the cross-head 28 and are accommodated for free rotation in a central aperture of the web 13. The cap 11 is formed with an axial, exterior boss 70 which is recessed to provide the inwardly-opening bore wherein the slide ring 68 and bearing 69 are housed, and the boss 70 is apertured centrally of its outer end to threadedly receive a sleeve 71 which telescopes over and rotatably receives the end of the stem 24' and bears at its inner end against the bearing assembly 69, so that rotation of the sleeve 71 acts through its threaded engagement with the end of the boss 70 to shift the abutment 66 longitudinally along the stem 24' for consequent contraction or expansion of the spring 47 and variation of the pressure exerted by said spring. A hand wheel 72, or similar device, may be fixed to the portion of the sleeve 71 projecting beyond the boss 70 for convenience in rotating the sleeve 71.

40 In the operation of certain tools, such as rock drills, it is of advantage to introduce water to the face of the tool, as is common practice, and the construction shown in Figure 6 is adapted for this purpose. The tool shank 56 shown in the drawings is provided with an axial bore or channel 73, such as is commonly provided in drills of certain types, and the impact head 23' and stem 24' are similarly provided with an axial bore or channel 74 opening entirely through the impact unit. The end of the bore 74 which opens adjacent the tool shank 56 is formed to telescope over and slidably receive the end of a tube 75 which extends within and is frictionally held by the bore 73 of the tool shank, so that a continuous flow passage is provided from the bore 74, through the tube 75 and to the bore 73 of the tool. The end of the stem 24' which reciprocates within the sleeve 71 is preferably worked to receive washers or packing material 76 which operates to seal the joints between said stem and thimble against leakage of water therethrough,

and the outer end of the thimble 71 is extended beyond the hand wheel 72 and arranged for connection with a hose, water line, or like means through which water may be fed to the apparatus.

Since many changes, variations, and modifications in the particular form, construction, and arrangement of the elements shown and described, may be had without departing from the spirit of my invention, I wish to be understood as being limited solely by the scope of the appended claims rather than by any details of the illustrative showing and foregoing description.

I claim as my invention—

1. A percussion tool comprising, an electric motor having a hollow driven shaft, an impact assembly reciprocable axially of said shaft, spring means normally and yieldably urging said impact assembly outwardly of said shaft in one direction, and cam means engaging with said impact assembly and operable as an incident of motor shaft rotation to intermittently retract said assembly against the pressure of said spring.

2. A percussion tool comprising, a housing, an electric motor field assembly fixedly carried by said housing, an electric motor armature assembly rotatably carried by said housing in operative association with said field assembly, a bore axially through the driven shaft of said armature assembly, an impact assembly reciprocably associated with said bore, spring means yieldably urging said impact assembly in one direction outwardly of said bore, and cam means engaging said impact assembly and operable as an incident of armature shaft rotation to intermittently retract said impact assembly against the pressure of said spring.

3. In a percussion tool, an electric motor having a hollow driven shaft, an impact assembly reciprocable axially of and held against rotation within said shaft, spring means normally and yieldably urging said impact assembly outwardly of said shaft in one direction, and cam means rotatable with said shaft in engagement with said impact assembly to intermittently retract said assembly against the pressure of said spring.

4. In a percussion tool, an electric motor having a hollow driven shaft, an impact assembly reciprocable axially of and rotatable within said shaft, spring means normally and yieldably urging said impact assembly outwardly of said shaft in one direction, and cam means held against rotation in engagement with said impact assembly to intermittently retract said assembly against the pressure of said spring as an incident of shaft rotation.

5. In a percussion tool having an electric motor formed with a hollow driven shaft, an impact assembly comprising a head and fixedly-associated stem coaxial within and reciprocable relative to said shaft, spring means yieldably urging said impact assembly toward one limit of its range of reciprocation, a cross-head on the impact assembly stem exteriorly of said shaft, and a cam track in engagement with said cross-head and operable as an incident of shaft rotation to intermittently retract the impact assembly against the pressure of said spring.

6. In a percussion tool having an electric motor formed with a hollow driven shaft, a stem coaxial within and reciprocable relative to said shaft, an impact head on one end of said stem, a cross-head on the other end of said stem exteriorly of said shaft, spring means yieldably urging said impact head outwardly of said shaft, a resiliently-positioned tappet in axial alignment with said impact head and for engagement therewith at an outer limit of the range of impact head travel, means for operatively associating a tool with the end of said tappet remote from said impact head, and cam means engaging said cross-head for intermittent retraction of the impact assembly against the pressure of said spring.

7. In a percussion tool having an electric motor formed with a hollow driven shaft, an impact assembly comprising a head and fixedly-associated stem coaxial within and reciprocable relative to said shaft, means slidably engaging between said impact assembly and shaft for rotation of the former with the latter, spring means yieldably urging said impact assembly toward one limit of its range of reciprocation, a cross-head fixed to the impact assembly stem exteriorly of said shaft, and a fixed cam track in engagement with said cross-head operable as an incident of shaft rotation to retract the impact assembly against the pressure of said spring.

8. In a percussion tool having an electric motor formed with a hollow driven shaft, an impact assembly comprising a head and fixedly-associated stem coaxial within and reciprocable relative to said shaft, means slidably engaging said impact assembly to hold said assembly against rotation with said shaft, spring means yieldably urging said impact assembly toward one limit of its range of reciprocation, a cross-head fixed to the impact assembly stem exteriorly of said shaft, and a cam track rotatable with said shaft in engagement with said cross-head and operable as an incident of such rotation to retract the impact assembly against the pressure of said spring.

9. In a percussion tool having a housing, an electric motor operatively and coaxially within said housing, and a hollow driven shaft in said motor, an impact assembly coaxially within, reciprocable relative to, and extending at each end beyond said shaft, an impact head on one end of said assembly, a cross-head fixed to the other end of said assembly, spring means normally urging the head end of said assembly to the limit of its extension relative to said shaft, cam means engaging said cross-head and operable as an incident of shaft rotation to intermittently retract said assembly against the pressure of said spring, a tappet reciprocably carried by said housing in axial alignment with said impact assembly adjacent and in position to be engaged by the head of said assembly, means for associating a tool shank in engagement with the end of said tappet remote from said head, and spring means engaging between said tappet and housing to resiliently and adjustably position said tappet.

DAVID L. GARRETT.
